UNITED STATES PATENT OFFICE.

GEORGE FINN, OF NEWARK, NEW JERSEY.

SELF-HEATING SAD-IRON.

1,203,515.

Specification of Letters Patent. Patented Oct. 31, 1916.

Application filed May 29, 1914. Serial No. 841,724.

To all whom it may concern:

Be it known that I, GEORGE FINN, a citizen of the United States, and a resident of Newark, in the county of Essex and State of New Jersey, have invented certain new and useful Improvements in Self-Heating Sad-Irons, of which the following is a specification.

The invention relates to improvements in self-heating sad irons, and it consists in the novel features, structure and combinations of parts hereinafter described, and particularly pointed out in the claims.

One object of the invention is to provide a new and improved self-heating sad iron capable of convenient construction and use and possessing special features of advantage with respect to the draft regulation, whereby efficient combustion is secured and proper heating of the iron attained.

The invention will be fully understood from the detailed description hereinafter presented, reference being had to the accompanying drawings, in which:

Figure 1 is a top view of a sad iron constructed in accordance with and embodying the invention; Fig. 2 is a vertical longitudinal section of the same on the dotted line 2—2 of Fig. 1; Fig. 3 is a vertical transverse section of the same on the dotted line 3—3 of Fig. 1, and Fig. 4 is a detached bottom view of the cover plate of the iron.

In the drawings 10 designates the body of the sad iron, 11 the top plate or cover thereof, and 12 the handle secured to said plate 11. The body 10 is hollow to receive the combustible material and elliptical in horizontal section, being pointed at both ends, as illustrated, whereby either end may be used as the forward end of the iron in ironing, said ends corresponding exactly with each other. In the opposite sides of the body 10 are draft apertures 13, which open into the interior of the body 10 below the downwardly and inwardly converging flanges 14 constituting a part of said body and which are elongated, as shown in Fig. 2, and correspond with each other. The draft apertures 13 are preferably circular, and by preference three of said apertures are formed in each side of the body 10, and said apertures are of such proportion with relation to the body of the iron that no dampers are required therefor, it being entirely

proper in the construction of iron herein presented that said apertures 13 remain constantly open. The flanges 14 afford convenient air spaces behind which the apertures 13 are located, and prevent the charcoal or other combustible material from escaping through the apertures 13. The flanges 14 also centralize the charcoal or other combustible material within the body 10 and aid in enabling the combustible material to maintain a substantially uniform temperature throughout said body. The upper edges of the body 10 present uniform horizontal surfaces except at opposite sides of said body, where standards 15 are formed, being cast integrally with the body 10 to receive the transverse rod or pin 16 by means of which the cover 11 may be detachably secured upon the body 10.

The cover 11 is a casting having an elliptical outline corresponding with the outline of the body 10 and recessed at its opposite side edges, as at 16^a, to fit upon the standards 15 extending upwardly from the side edges of the body 10. The cover 11 is of special importance in securing convenience both in the manufacture and use of the iron and in the attainment of proper combustion, and said cover is formed in its end portions with upwardly extending recesses or chambers 17 apertured at their upper ends, as at 18, said chambers and apertures extending along both sides of each end of the cover and there preferably being three apertures 18 at each side of each end of the cover. At the extreme ends of the cover 11 are provided downwardly extending lugs 19 which enter the end portions of the body 10 and serve to readily position the cover on said body. On the lower side of the cover 11 are two slideable damper plates 20, which correspond with each other, and one of which is below one end of the cover and the other below the other end of the cover and their purpose being to enable the user of the iron to regulate the draft through the openings 18 at the ends of the cover. In Fig. 4 I illustrate one of the damper plates as having been moved to a position to close the openings 18 above it, and the other damper plate 20 as moved to a position partly uncovering the recess or chamber 17 leading to the other set of openings 18. The material of the cover 11 is extended upwardly at the opposite ends

of the cover to form the chambers or recesses 17 which extend along each side of each end of the cover, and the damper plates 20 are secured against the lower face of the cover 5 and are slidable longitudinally so as to entirely or more or less close said recesses or chambers 17, each damper plate 20 being independently movable in a longitudinal direction.

- 10 Each damper plate 20 is formed with a longitudinal slot 21 clearly indicated by dotted lines in Fig. 4, and each slot receives a portion of a rivet 22 which extends downwardly through the cover 11 and the slot 21 and a spring 23 and is upset at its lower end against said spring 23. There are two rivets 22, one for each damper plate 20, and both rivets are utilized, as shown in Fig. 2, in securing the handle supporting bar 24 upon the cover 11, said rivets extending downwardly through said bar, through integral bosses 25 formed on the upper surface of the cover 11 and through said cover and the slots 21 and spring 23 and being upset 25 at their lower ends against said spring. The damper plates 20 are formed with upwardly projecting thumb-pieces 26 which extend upwardly through slots 27 in the cover plate 11, and said thumb-pieces 26 may be utilized 30 for sliding the damper plates 20 frontwardly or rearwardly, as occasion may require. The thumb-pieces 26 are exposed at the upper side of the cover or plate 11, and hence the damper plates may be adjusted so as to more 35 or less close the chambers or recesses 17 without removing the cover plate from the body of the iron. When the cover plate is not on the body of the iron the damper plates 20 may be readily moved longitudinally by the 40 pressure of the thumb or thumbs of the user thereon. The outer end and side portions of the damper plates 20 conform to the edge outline of the cover plate 11, and said cover plate on its lower surface is recessed, as at 45 28, to a depth about equal to the thickness of said plates 20.

The spring 23 is of special importance in that it retains the damper plates 20 in position against the lower surface of the cover 50 11, and said spring 23 is a flat leaf-spring slightly bowed and in its normal condition prior to being applied to the iron being more greatly bowed than is represented in the drawings. When the spring 23 is secured by 55 the rivets 22 it becomes less bowed than when in its normal condition, and therefore the end portions of the spring 23 become rather firmly pressed against the lower surfaces of the damper plates 20 and serve to 60 yieldingly, though firmly, hold said plates up against the lower surface of the cover 11.

The cover 11 is formed at its opposite sides and in line with the inner edges of the recesses 16 with vertical lugs 29, which match 65 and set against the standards 15 formed on

the body of the iron, as shown in Figs. 1 and 3, and said lugs 29 and standards 15 are correspondingly apertured to receive the rod or pin 16 by which the cover is connected with the body of the iron. The other a pair of 70 flanges 30 which connect the lugs and strengthen the cover and form between them a channel, as shown in Fig. 2, along which the rod or pin 16 may extend.

The invention made the subject hereof was 75 devised as an improvement on the sad iron shown in the Letters Patent of the United States No. 705,573 granted to me July 29, 1902. I have found that with the low recesses or chambers 17 at each end of the 80 cover and provided with the top outlet openings at each side of each end, the draft through the iron may be regulated with great efficiency, and said recesses constitute one of the important features of the present 85 invention and when used permit the employment of valveless or gateless inlet draft apertures 13. The dampers 20 arranged close up under the cover and independently slidable aid very much in the draft regulation, and securing the said dampers yielding 90 against the lower face of the cover by means of the spring 23 is important in that the dampers may yield to variations in temperature without binding and at all times 95 keep their position.

What I claim as my invention and desire to secure by Letters Patent, is:

1. A self-heating sad-iron comprising a hollow body having air inlets in the lower portion of its sides, a cover for said body and a handle on said cover, said cover having a shallow upwardly extending open recess in the lower side of its end portion and a series of openings along the top of said recess, and said cover also having on its lower side a slidable damper having an exposed thumb-piece for more or less closing said recess.

2. A self-heating sad-iron comprising a hollow body having a pointed end and air inlets at its lower portion, a cover for and conforming to the outline of said body and having at its pointed end a draft outlet, a slidable damper on the lower side of said 115 cover having an exposed thumb-piece for more or less closing said outlet, a spring secured to the cover and flexed against said damper for yieldingly pressing the same against the cover, and a handle on said 120 cover, said damper having a guide slot therein and said spring and handle being secured to the cover by a rivet which extends through said slot.

3. A self-heating sad-iron comprising a 125 hollow body having air inlets in the lower portion of its sides and a pointed end, a cover for and conforming to the outline of said body and having at its pointed end and extending along the sides thereof an up- 130

wardly extending open shallow recess and a series of top outlet openings from the sides of said recess, a handle for the iron secured to said cover, and a slideable damper on the lower side of said cover having an exposed thumb-piece for more or less closing said recess.

Signed at New York city, in the county of New York and State of New York, this 27th day of May, A. D. 1914.

GEORGE FINN.
